Milton Tibbets.

UNITED STATES PATENT OFFICE.

MILTON TIBBETTS, OF DETROIT, MICHIGAN.

MOTOR-VEHICLE.

1,325,059.

Specification of Letters Patent. Patented Dec. 16, 1919.

Application filed December 9, 1916. Serial No. 136,012.

To all whom it may concern:

Be it known that I, MILTON TIBBETTS, a citizen of the United States, and resident of Detroit, Wayne county, State of Michigan, have invented certain new and useful Improvements in Motor-Vehicles, of which the following is a specification.

This invention relates to wind shields for motor vehicles and it has particular reference to the form of and mounting of the sash or sashes of such a wind shield.

One of the objects of the invention is to provide means for supporting a wind shield sash so that it may be slightly raised from the edge of the support upon which it rests and then be adapted to swing clear of the support to leave a clear space above the support.

Another object of the invention is to provide means for automatically guiding the wind shield sash in its various movements of being lifted off of the support and into a position to provide a clear space.

Another object of the invention is to provide automatic means for moving the two sashes of a wind shield out of line at the commencement of the swinging movement of one of the sashes in changing from its closed to its open position.

Other objects of the invention will appear from the following description taken in connection with the drawings which form a part of this specification and in which:

Figure 1 is a rear elevation of an illustrative form of wind shield embodying this invention;

Fig. 2 is an edge view of the wind shield shown in Fig. 1, looking toward the left hand end of Fig. 1 and showing the sash in raised position in full lines and in lowered position in dotted lines;

Fig. 3 is an enlarged detail edge view also looking inward at the left hand end of the wind shield shown in Fig. 1 and showing the upper sash moved out of alinement with the lower sash.

Fig. 4 is a view similar to Fig. 3 except that the upper sash of the wind shield has been lowered to a position at the rear of the lower sash;

Fig. 5 is a detail vertical section on the line $\alpha-\alpha$ of Fig. 1, and Fig. 6 is an en-

larged detail edge view of the right hand end of the wind shield shown in Fig. 1, 55 showing the sashes in alinement.

In the drawings 4 represents the lower sash or supporting part of a wind shield and 5 is the upper movable sash, these sashes when in normal or operative position being 60 in line one above the other. The lower sash may, if desired, be braced as by the brace rods 6.

As shown, the sash 5 rests with its full weight upon the upper edge of the lower 65 sash or supporting part 4 and these meeting edges of the two sashes may be made to incline forwardly and downwardly as shown at 4' and 5' in Figs. 3 and 5. The exact shape of these meeting edges is not material 70 except that the highest part of the edge of the support should be above and rearwardly of the lowest part of the edge of the sash 5 so that water striking the upper sash will pass over the joint and not through it. 75

In order that the above described form of water tight joint may be used between the meeting edges of the upper sash and the supporting part, the present invention contemplates a supporting means for the upper 80 sash that will permit it to be lifted bodily to clear the upper edge of the supporting part 4 and then moved to provide a clear ventilating space above the supporting part of the wind shield. In the form shown the upper 85 wind shield sash is raised slightly to clear the edge of the lower sash and rearwardly out of line with the lower sash and then it is lowered by a relative endwise motion of pure translation in a circular path. One 90 end of the two sashes is connected by a link arm 28 pivoted to the lower sash at its top at 29 and extending at an inclination and pivoted to a bracket 30 on the upper sash. At the other end of the sashes a link arm 31 95 is pivotally connected to the upper sash at 32 and is pivotally connected at its lower end to a bracket 33 extending outwardly from the top of the lower sash, thus making the arm 31 stand at an inclination parallel to the arm 28. This inclined arrangement of the link arms permits the upper sash when moved to the right in Fig. 1 to be automatically elevated above the lower sash during the first part of the swinging operation 100

while being maintained constantly in a ver-

tical plane. The rearward movement of the upper sash is secured by the action of cam surfaces on pivot sleeves 34 and upon the lower ends of the link arms 28 and 31 as shown at 35. The link arms have sliding pivotal connections with the sleeves 34 thus permitting these link arms to be moved rearwardly to the position shown in Fig. 3. The cam surfaces may be of any desired form 10 which will have the effect of moving the arms as desired and consequently lengthwise of the pivot joint, and in Figs. 3 and 4 I have shown one form of cam for doing this. In this particular form the sleeve 34 has an inclined surface 36 against which bears a similar surface on the link arm and it will be understood that there is on the other side of the sleeve another inclined surface like 36 and having the same inclination but in the 20 opposite direction, thus forming practically a cam groove into which a portion of the link arm passes. The result is that when the link arms are turned in one direction the upper sash is moved out of line with the 25 lower sash, and when turned in the opposite direction the two sashes are automatically moved into line. In the particular form shown it is necessary by slight pressure on the parts to bring the two cam surfaces into 30 operation, but it is of course obvious that this might be done automatically as by a spring. In this form of the invention I have provided bolts 37 on the ends of the upper sash adapted to lock the sash in position on the supporting part 4, thus preventing 35 accidental turning of the sash upon the link arms.

It will be understood that when the upper sash is moved rearwardly an opening is 40 formed between the sashes permitting the passage of a current of air. Also when the upper sash is dropped to its lowered position in the rear of the lower sash, a clear space is provided for ventilation above the 45 supporting part 4. The sash may be manipulated by the handles 16.

Having thus described my invention, what is claimed is:—

1. A wind shield comprising a lower sash, 50 an upper sash resting thereon, and parallel link connection between said sashes guiding the upper sash by an endwise movement to a position against the lower sash, the arms of said link connection being at such an incline 55 to the meeting edges of the sashes that the upper sash is raised from the lower sash at the commencement of the folding operation.

2. A wind shield comprising a lower sash, an upper sash resting thereon having bevelled meeting edges, and parallel link connection between said sashes permitting the upper sash to be folded against the lower sash by an endwise movement of the former, the arms of said link connection being at 65 such an incline to the meeting edges of the

sashes that the upper sash is raised from the lower sash at the commencement of the folding operation.

3. A windshield comprising a lower sash, and an upper sash, the upper sash being arranged normally in a plane with the lower sash, parallel link arms pivotally connecting said sashes and permitting the sashes to have relative swinging motion in parallel planes, and means for guiding the upper 75 sash to a position out of line with the lower sash at the commencement of the swinging motion.

4. A windshield comprising a lower sash, and an upper sash, the upper sash being arranged normally in a plane with the lower sash, parallel link arms pivotally connected to said sashes permitting the sashes to have relative swinging motion in parallel planes, and cams connected with said link arms 85 adapted to move the upper sash out of line with the lower sash at the commencement of the swinging motion.

5. A windshield comprising a lower sash, and an upper sash, the upper sash being arranged normally in a plane with the lower sash, parallel link arms pivotally connected to said sashes permitting the sashes to have relative swinging motion in parallel planes, and cams connected with said link arms 95 adapted to move the upper sash out of line with the lower sash at the commencement of the swinging motion, and adapted to guide the sashes into line at the end of the upper swinging motion.

6. A windshield comprising a lower sash, an upper sash movable relatively to said lower sash, means for causing the upper sash to be raised slightly as force is imparted thereto to effect the separation of the sashes, 105 and means for carrying the upper sash rearwardly out of line with the lower sash in the continued movement thereof, the support for said upper sash permitting the lowering of the same by an edgewise movement into a 110 position in the rear of the lower sash.

7. A windshield comprising a lower sash, an upper sash in line therewith, the said sashes having beveled meeting edges, means whereby the upper sash will be raised 115 slightly as a swinging movement is imparted thereto in separating the upper sash from the lower sash, and means for guiding the upper sash rearwardly out of line with the lower sash, the support of said upper sash 120 permitting it to be lowered by an edgewise movement into a position in the rear of the lower sash.

8. A windshield comprising a lower sash, an upper sash in line therewith and resting 125 thereon, parallel link arms pivotally connected to said sashes and standing at such an incline to the meeting edges that the upper sash will be slightly raised at the commencement of the swinging motion, and 130

means on said arms for moving the upper sash out of line with the lower sash before the commencement of the downward motion.

9. A windshield comprising a lower sash 5 and an upper sash, the upper sash being arranged normally in a plane with the lower sash, parallel link arms pivotally connected to said sashes permitting the sashes to have relative swinging motion in parallel planes, 10 sliding connection for the pivot joints on the lower sash, and interengaging cam surfaces on the parts of said joints adapted to move the cam arms laterally until the sashes 15 are out of line after a slight swinging motion.

10. A windshield comprising a lower sash

and an upper sash, the upper sash being arranged normally in a plane with the lower sash, parallel link arms pivotally connected to said sashes permitting the sashes to have 20 relative swinging motion in parallel planes, sliding connection for the pivot joints on the lower sash, and interengaging cam surfaces on the parts of said joints adapted to move the cam arms laterally until the sashes 25 are out of line after a slight swinging motion, and adapted to guide the sashes into line at the end of the upward swinging motion.

In testimony whereof I affix my signature.

MILTON TIBBETTS.
